UNITED STATES PATENT OFFICE.

SILAS M. FORD, OF ST. PAUL, MINNESOTA.

ROOFING-STRIP.

1,203,598.

Specification of Letters Patent. Patented Nov. 7, 1916.

Application filed March 6, 1916. Serial No. 82,381.

To all whom it may concern:

Be it known that I, SILAS M. FORD, a citizen of the United States, residing at St. Paul, in the county of Ramsey and State of Minnesota, have invented certain new and useful Improvements in Roofing-Strips, of which the following is a specification.

One object of my invention is to provide in roofing strips of fancy design means for giving a heavy appearance to the lower edges of the shingles.

Another object of my invention is to provide in roofing strips a reinforcement at the lower edge and extending diagonally across the roofing strip to stiffen it.

Another object of my invention is to provide in a roofing strip a positive lock in two directions for different layers of roofing strips.

Another object of my invention is to provide in a roofing strip having a diamond shaped design, a drip to prevent water from running back under the roofing strip.

With these and incidental objects in view the invention consists of certain novel features of construction and combination of parts, the essential elements of which are hereinafter described with reference to the drawings which accompany and form a part 30 of this specification.

In the drawings Figure 1 is a plan view of a portion of a roof covered with roofing strips of my improved design, Fig. 2 being a side elevation of the same. Fig. 3 is a 35 plan view of my improved roofing strips, Fig. 4 being a front elevation of the same, while Fig. 5 shows a development of the roofing strip, shown in Figs. 3 and 4. Fig. 6 is a plan view of a modification of my 40 preferred construction. Fig. 7 is a cross section taken on the line "BB", Fig. 1, to show the manner in which the folds of the strips interlock. Fig. 8 is a plan view of a strip before it is folded to form the roofing strip, 45 shown in Fig. 6, to show the development of the folds. Fig. 9 is a section of a portion of a strip, as shown in Fig. 3, taken on the line "AA", viewed in the direction of the arrows, to show the folds in the roofing 50 strip, and Fig. 10 is a front elevation of the modification of my preferred construction shown in Fig. 6.

In my preferred construction I take a strip of prepared roofing of any nature, such 55 as strip 1, Fig. 5, and make folds along the lines 2 and 3, the folds being parallel, and

then make folds along the line 2' and 3', these folds also being parallel, the result being folds crossing each other at right angles at the points 4, as shown in Figs. 3 and 4. With roofing strips made in this manner, it is evident that with the roofing strip 5, Fig. 1, laid upon the roofing strip 6, Fig. 1, the folds of the lower strip will register and lock with the folds of the upper strip, as plainly shown in Fig. 10, which is a cross-section taken on the line "BB", Fig. 1. It is therefore apparent that the folds which in each roofing strip run at right angles to each other and intersect in substantially the center of the roofing strip, will serve as an interlocking means for the superimposed strip, the lock running in both directions, and also that the roofing strips are stiffened in both directions by these folds.

It will be noted in Figs. 1, 3 and 5 that the folds are made in such manner in the strips, that there is a projection 7 extending beyond the main portion of the roofing strip, and which when the strips are laid upon a roof project down below the corner formed in the roofing strip below by the intersection of the two folds, the projection 7 being reinforced by the two folds.

As the folds are made one right-handed and one left-handed, it is apparent that no matter which way the strip is cut from a sheet of roofing, the fibers will extend in one direction on the top of the projection 7, and the fibers in the fold below the projection 7 will extend across the fibers of the top sheet, so that the reinforcement is of two sheets of materials having grains running cross-wise of each other. This serves as a drip, so that water running down the surface of the strip will fall below the corner between the folds of the strip next below and thus serve as an additional precaution against water being drawn up under the top roofing strip.

The strips would preferably be nailed at points 8, Fig. 1, which would be adjacent to, but not piercing the folds in the roofing strip, and as each of the roofing strips used on the roof is locked to the strips above and below, the entire roofing will be locked as one unit, but the folds will also be expansion joints, allowing expansion and contraction in all directions, so that the contraction and expansion will be held to that portion between expansion joints, and not accumulate at any one portion.

As an alternate construction, I fold a strip 9, Fig. 8, along lines 10 and 11, similar as described in the case of the strip 1 in Fig. 5, and then along lines 10' and 11', 5 producing a similar roofing strip, as shown in Figs. 6 and 7, but without the crossing of the folds in the individual strips.

It is evident that the stiffening of the 10 roofing strips above and below will be similar to that already described, and the projections 7 are provided in the same manner as heretofore described, but that the locking feature is omitted.

While I have described my invention and 15 illustrated it in particular designs, I do not wish it understood that I limit myself to these constructions, as it is evident that the application of my invention may be varied in many ways within the scope of 20 the following claims:

I claim:

1. As an article of manufacture a roofing strip having multiple parallel plaits formed therein running at an acute angle to the 25 lower edge of said roofing strip and a second series of parallel plaits running at a different acute angle with the lower edge of said roofing strip.

2. As an article of manufacture a roofing 30 strip having a series of multiple parallel plaits running diagonally across said roofing strip, and a second series of multiple parallel plaits running diagonally across said roofing strip and joining said first series of plaits.

3. As an article of manufacture a roofing strip having a series of diagonal plaits therein, and a second series of diagonal plaits crossing said first series of diagonal 35 plaits.

4. As an article of manufacture a roofing strip having a series of diagonal plaits therein, a second series of diagonal plaits crossing said first series, said two series of 40 diagonal plaits joining below the lower edge 45 of said roofing strip.

5. As an article of manufacture a roofing strip having therein a series of plaits running across the face of said roofing strip at one angle, a second series of diagonal plaits 50 running across the face of said roofing strip at a different angle, each one of the plaits in said first series crossing one of the plaits of said second series, said plaits being formed in one instance right-handedly, and in the 55 other instance left-handedly, so that a roof-

ing strip so formed may register and lock with a similar strip superimposed on said roofing strip in shingle fashion.

6. As an article of manufacture a roofing strip having therein a series of plaits running across the face of said roofing strip at one angle, a second series of plaits running across the face of said roofing strip at a different angle, each of said first series crossing one of the plaits of said second series, 60 said plaits being formed in one instance right-handedly and in the other instance left-handedly, so that a roofing strip so formed may register and lock with a similar strip superimposed on said roofing strip in 65 shingle fashion, each one of one series of plaits meeting one of the other series of plaits below the lower edge of said roofing strip.

7. As an article of manufacture a roofing 70 strip having therein a series of right-handed plaits running diagonally across said roofing strip, and a series of left-handed plaits running diagonally across said roofing strip, at an angle to said first series, each of the 75 right-handed plaits meeting one of the left-handed plaits below the lower edge of said roofing strip.

8. As an article of manufacture a roofing strip having a series of right-handed plaits 80 therein at an acute angle to the lower edge of said roofing strips, a series of left-handed plaits extending at a different acute angle across the face of said roofing strip, each 85 right-handed plait crossing one left-handed plait intermediate of the ends of said roofing strip and joining another left-handed plait below the lower edge of said roofing strip.

9. As an article of manufacture a roofing strip having folds therein adapted to serve 90 as a lock in two directions, with similar folds in a roofing strip placed on and above said roofing strip in shingle fashion.

10. As an article of manufacture a roofing strip having folds therein, said folds crossing 95 at intervals and serving as expansion joints for said strip.

11. As an article of manufacture a roofing strip having intersecting folds therein adapted to serve as locks between two of 100 said strips, one superimposed on the other in shingle fashion, and said lock fold being also adapted to serve as an expansion joint, allowing expansion in all directions.

SILAS M. FORD.
